FORM TOOL GENERATING FIXTURE

Walter F. Ross, Oakland County, Mich., assignor
to Motor Tool Manufacturing Company, De-
troit, Mich., a corporation of Michigan

Application November 4, 1944, Serial No. 561,988

12 Claims. (Cl. 51—100)

1

This invention relates to circular form tool grinding fixtures and has for its object to provide an arrangement in which the grinding of such form tools of complicated outline, and more especially of outline having abrupt variations in form, may be effected by the operator to conform with conditions imposed by the form of a master dummy with great facility and accuracy.

An important object of the said invention is to provide such a device in which a follower finger traverses the dummy and thereby limits the variable relationship of the work to the abrasive wheel, to secure the ground reproduction of the contour of the dummy on the work, and in which this relationship may be accurately and readily preserved throughout changes which may be made in the angularity of presentation of the abrasive wheel to the work such as may be necessary to the operator in the grinding of shoulders, steps, sharply bevelled outlines, and so forth.

More particularly it is an object of the said invention to provide for the coupled angular manual adjustment of the abrasive wheel and the follower finger whereby their points of contact with the work and with a master dummy, respectively, will be maintained in the same relation to the respective centers of angular adjustment of the said follower finger and the abrasive wheel support.

A further object is to provide for the adjustment of the abrasive wheel upon its reduction in diameter, as by dressing, to bring the arc of swinging of that portion of the periphery of the wheel presented to the work into radial conformity with the arc of swinging of the follower finger.

A still further object of the said invention is to provide for control of a work-carrying table in such manner that the work may be either manually fed toward the abrasive wheel, subject to limitations imposed by the master dummy, or allowed to automatically move with respect to the abrasive wheel under such influence and under the further influence of a weight or similar means biasing the work table in the direction of the abrasive wheel.

Still further objects or advantages additional or subsidiary to the aforesaid objects, or resulting from the construction or operation of the invention as it may be carried into effect, will become apparent as the said invention is herein-after further disclosed.

In carrying the invention into effect, I may adopt the novel construction and arrangement

2

of parts hereinafter described, by way of example, having reference to the accompanying drawings, wherein:

Figure 1 is a side elevation, shown partly in section, of a grinding machine embodying the said invention;

Figure 2 is a plan view of the same; and

Figure 3 is a similar view to Figure 2 illustrating a different operational position of the parts.

Similar characters of reference indicate similar parts in the several figures of the drawings.

10 16 indicates the fixed base structure of a grinding machine supporting a work table 11 which is subject to controlled longitudinal feed by mechanism (not shown) such as is common to such machines.

15 17 Mounted on the said table 11 is a transversely slidable table 13 which I show as being biased for such transverse movement by weighted lever 14 linked to the back of the said table 13 and 15 is a hand feed screw by means of which transverse adjustment of the said table may be effected. The table 13 is shown as being provided with an 20 abutment 16 on its under side which may impinge against a stop 17 on the end of the said feed screw 15 whereby the operation of the said feed screw may be effective in controlling adjustment of the said table but, at the same time, 25 permitting the said table to be freely moved without interference of the said feed screw in a direction to positions forward of the said stop. The said work table 13 is hollow or has suitable 30 spacing provided on its under side to accommodate linkage mechanism, as will be explained, 35 and also has a suitable opening in the top thereof to provide clearance for the movement of a finger post 12 operated by the said linkage mechanism.

40 18 19 Mounted on either end portions of the said transversely slidable table 13 are tail stocks 18 and 19, hereinafter referred to as the left hand and right hand tail stocks, respectively, the left hand tail stock carrying two centers 20 and 21 45 in parallel horizontally spaced relation to each other, and the right hand tail stock 19 similarly carrying two centers 22 and 23 in axial alignment with the said centers 20 and 21. The tail stocks 18 and 19 are adjustable toward and from 50 one another on the said table 13 to accommodate work or arbors of varying lengths. In the present example an arbor 24 is shown as carried between the centers 20 and 22 and an arbor 25 between the centers 21 and 23, the arbor 24 having a pulley 26 mounted thereon which is coupled by the belt

55

27 with the pulley 28 of a motor 29 carried on the tail stock 19.

The arbor 35 has mounted thereon a dummy 36 having the profile of the work to be ground, which profile in this instance is characterized by a central portion 37 of conventionally cylindrical form, terminating at one end in a 90° shoulder 38 and at the other end in a bevelled shoulder 39, the enlarged end portions of the dummy 36 having concaved cylindrical surfaces 40 and 41. These various forms of profile are to be ground on work, such as a rotary form cutter 42, mounted on the arbor 24 and present a grinding problem which the present invention and the mechanism described herein solves in a simple and highly efficient manner. For the sake of clear illustration and simplicity the solid outline of the work is shown without illustrating the presence of teeth or grooves which are characteristic of a rotary cutter and which may be of various forms.

43 is a follower finger carried by the upper end of the finger post 12 to engage the surface of the said dummy 36 for the purpose of causing the transversely slidable table 13 to move laterally under the influence of the weighted lever 14 in conformity with the outline of the said dummy over which the said follower finger 43 passes as the table 11 is fed longitudinally. It is not intended that the dummy 36 rotate during such operation although it may be rotated from time to time as by hand between operations to provide a new wearing surface for contact with the finger 43, if thought necessary or desirable. The work, however, is rotated through the agency of the motor 29 during such movements of the table in order that a suitable grinding wheel, such as 44, may effect the circular grinding of the work in conformity with the profile determined by the cooperative action of the follower finger 43 and the dummy 36.

It will be observed that, in the example, the stop 17 of the feed screw 15 is capable of being moved to a spaced position from the abutment 16 of the table 11 so that the said table may be free to move laterally under the influence of the weighted lever 14 to an extent limited by the contact of the dummy 36 with the follower finger 43. Thus, with the table so freely movable, such outlines as the concaved cylindrical surfaces 40 and 41 of the dummy may be ground in reproduction on the work 42 by the abrasive wheel 44 by simply permitting the said table 11 to adjust itself laterally under the influence of the progression over the said profiled surfaces 40 and 41 of the said dummy of the point of the follower finger 43, when required longitudinal movement is imparted to the said table by the regularly provided longitudinal feed mechanism common to grinding machines.

It will be readily understood that this generation of the said profiled form on the work is due to the fact that the motions of the dummy travelling over the follower finger are imparted, through the corresponding motions of the table 11, to the work 42 carried in parallel with the said dummy by the said table 11.

In many form tools of complicated outline it is frequently impossible to have the follower finger define such outline in a continuous manner or with an abrasive wheel dressed to only one peripheral form. For instance, in the example shown, the 90° shoulder 38 could not be ground with the radially dressed wheel 44 as shown in Figure 2, neither does the bevelled

shoulder 39 offer itself to being properly reproduced by such a wheel. Moreover, neither of these shoulders, and especially the first, lend themselves to a continuous generating motion of the dummy over the finger 43 as will be obvious, and, in cases such as these, I propose by hand adjustment of the feed screw 15 to bring the feed screw stop 17 into controlling contact with the abutment 16 of the table 11 whereby required movement of the dummy 36 in relation to the follower finger 43 may be effected manually by operation of the said feed screw 15.

It is also desirable, in effecting the grinding of such shoulders as 38 and 39, that a follower finger such as 45 of suitably modified form be substituted for the finger 43 and be presented at an angle to the shoulder to conform with the angle at which a correspondingly substituted abrasive wheel 46 is presented to the work, as shown in Figure 3. To enable this to be done without disturbing the working relationship as to position of motion between the dummy and its follower finger, and between the work and the grinding wheel, I provide means for coupling the grinding wheel and the follower finger together for co-related angular adjustment so that the point of the follower finger during such adjustment will traverse the same arc and degree as does the active grinding point of the abrasive wheel.

To accomplish this in a simple manner, I may mount the spindle 47 of the abrasive wheel on a turn-table 48 mounted on a suitable pedestal 49. This pedestal is shown as being provided with a stationary clamp bracket 50 extending forwardly beneath the table 11 to support a pivot 51 on which a finger swivel bracket 52 is mounted. This bracket carries the finger post 12, previously referred to, and also has connected thereto, in spaced relation to and on opposite sides of the said pivot 51, links 53 and 54, the rear ends of which links are connected at 55 and 56 to the under side of the said turn-table 48.

As a result of this linkage any angular adjustment of the grinding wheel, by rotation of the turn-table 48, will be accompanied by corresponding angular adjustment of the finger swivel bracket 52 as will be clearly observed by a comparison of Figures 2 and 3. When such an adjustment is made, as for the purpose of grinding the form of the shoulder 38 on the work, the table 11 is moved longitudinally and laterally to bring the said shoulder 38 into contact with the follower finger 45 which will bring the work into correct position with respect to the abrasive wheel for the grinding of such a shoulder on the said work; and the required motions of the work relative to the abrasive wheel, for effecting such operation, may then be readily and accurately instituted by the manual longitudinal and lateral adjusting of the said table 11 by feed means provided and to the extent required.

As far as the grinding of the form of the shoulder 39 on the work is concerned, the following of the contour may be effected by hand control of the table where the angle of the shoulder is so steep as to render this necessary or desirable; but where the angle is such that it does not preclude it, the feed screw stop 17 may be released from the feed table abutment 16 to permit the follower finger to freely ride the angular surface and thereby directly and solely control the lateral movement of the said table

11 during its longitudinal movement relative to the said follower finger.

57 indicates a suitable type of wheel dresser which may be interchangeable from one type to another according to the form to be dressed on the abrasive wheel and 58 is a micrometer screw for moving the dresser into the wheel as required.

In order to maintain the working point on the wheel at a determined distance from the center of rotation of the turn-table 48 so that its arc of swinging adjustment will conform with that of the finger, the abrasive wheel after dressing should be moved up to the work to an extent equal to the amount dressed of the periphery of the wheel. For such purpose it may be considered that the support 59 on which the abrasive wheel assembly is mounted is slideable to some extent as in dove tail ways 60 formed on the table 48 under the influence of the micrometer adjusting screw 61.

Thus if the dresser adjusting screw 58 be advanced, say, .005" in dressing the abrasive wheel the wheel adjusting screw 61 is thereafter accordingly advanced .005" to compensate for the reduction of the grinding wheel radius, as will be well understood. As there is a limit to the extent to which it may be practical to move up the abrasive wheel in the manner described, it may be necessary to discard the grinding wheel when its radius has been reduced to such limitation and a new wheel substituted therefor after retraction of the wheel support 59 to its original centralized position on the turn-table 48.

With an arrangement such as that described rapid and accurate reproduction of complicated forms on a form tool cutter from a master dummy may be effected with great facility.

This invention may be developed within the scope of the following claims without departing from the essential features of the said invention, and it is desired that the specification and drawing be read as being merely illustrative of a practical embodiment of the said invention and not in a strictly limiting sense.

What I claim is:

1. In a circular form tool grinding device of the class described, a work-guiding table, a work-grinding abrasive wheel, a profiled stop carried by said table having the form of the envelope of the work as it is to be ground, a follower finger presented to a longitudinal line on the profiled surface of said stop, means for adjusting the angularity of presentation of the said wheel and the said follower to the work and to a dummy respectively, and means for adjustably moving said wheel toward the work perpendicular to the axis of the wheel, while maintaining the relationship of the axis of angular setting of the wheel to the angular setting axis of the follower.

2. In a circular form tool grinding device of the class described, a work-guiding table, a work-grinding abrasive wheel, a profiled stop carried by said table having the form of the envelope of the work as it is to be ground, a follower finger presented to a longitudinal line on the profiled surface of said stop, means coupling said wheel to said follower for coordinated angular adjustment relative to the work and to said profiled stop, respectively, and means for adjustably moving said wheel toward the work perpendicular to the axis of the wheel, while maintaining the relationship of the axis of angular setting of the wheel to the angular setting axis of the follower.

3. In a circular form tool grinding device of the class described, a work-guiding table, a turn-

table, a work-grinding abrasive wheel mounted on said turn-table for angular adjustment to the work, a profiled stop carried by said table having the form of the envelope of the work as it is to be ground, a follower finger presented to a longitudinal line on the profiled surface of said stop, a finger swivel bracket coupled to said turn-table whereby angular adjustment of both said wheel and said follower finger may be coordinated, adjustable means for synchronizing the radial swinging arc of the working contact point of said wheel with the radial swinging arc of the contact point of said finger, and means for adjustably moving said wheel toward the work perpendicular to the axis of the wheel, while maintaining the relationship of the axis of angular setting of the wheel to the angular setting axis of the follower.

4. In a circular form tool grinding device of the class described, a work-guiding table, a work-grinding abrasive wheel, a profiled stop carried by said table having the form of the envelope of the work as it is to be ground, a normally stationary follower finger presented to a longitudinal line on the profiled surface of said stop, means for adjusting the angularity of presentation of the said wheel and the said follower to the work and to said profiled stop, respectively, for the purposes specified, releasable manual means for feeding said work-table toward said wheel, and means biasing said table in the direction of said wheel when said manual feed is released.

5. In a circular form tool grinding device of the class described, a work-guiding table, a work-grinding abrasive wheel, a profiled stop carried by said table having the form of the envelope of the work as it is to be ground, a normally stationary follower finger presented to a longitudinal line on the profiled surface of said stop, means coupling said wheel to said follower for coordinated angular adjustment relative to the work and to said profiled stop, respectively for the purposes specified, releasable manual means for feeding said work-table toward said wheel, and means biasing said table in the direction of said wheel when said manual feed is released.

6. In a circular form tool grinding device of the class described, a work-guiding table, a turn-table, a work grinding abrasive wheel mounted on said turn-table for angular adjustment to the work, a profiled stop carried by said table having the form of the envelope of the work as it is to be ground, a normally stationary follower finger presented to a longitudinal line on the profiled surface of said stop, a finger swivel bracket coupled to said turn-table whereby angular adjustment of both said wheel and said follower finger may be coordinated, for the purposes specified, releasable manual means for feeding said work-table toward said wheel, and means biasing said table in the direction of said wheel when said manual feed is released.

7. In a circular form tool grinding device of the class described, a work-guiding table, a work-grinding abrasive wheel, a profiled stop carried by said table having the form of the envelope of the work as it is to be ground, a follower finger presented to a longitudinal line on the profiled surface of said stop, means for adjusting the angularity of presentation of the said wheel and the said follower to the work and to said profiled stop, respectively, adjustable means for synchronizing the radial swinging arc of the working contact point of said wheel with the radial swing-

ing arc of the contact point of said finger, releasable means for feeding said work-table toward said wheel, and means biasing said table in the direction of said wheel when said manual feed is released.

8. In a circular form tool grinding device of the class described, a work-guiding table, a work-grinding abrasive wheel, a profiled stop carried by said table having the form of the envelope of the work as it is to be ground, a follower finger presented to a longitudinal line on the profiled surface of said stop, means coupling said wheel to said follower for coordinated angular adjustment relative to the work and to said profiled stop, respectively, adjustable means for synchronizing the radial, swinging arc of the working contact point of said wheel with the radial swinging arc of the contact point of said finger, releasable manual means for feeding said work-table toward said wheel, and means biasing said table in the direction of said wheel when said manual feed is released.

9. In a circular form tool grinding device of the class described, a work-guiding table, a turn-table, a work-grinding abrasive wheel mounted on said turn-table for angular adjustment to the work, a profiled stop carried by said table having the form of the envelope of the work as it is to be ground, a follower finger presented to a longitudinal line on the profiled surface of said stop, a finger swivel bracket coupled to said turn-table whereby angular adjustment of both said wheel and said follower finger may be coordinated, adjustable means for synchronizing the radial swinging arc of the working contact point of said wheel with the radial swinging arc of the contact point of said finger, releasable manual means for feeding said work-table toward said wheel, and means biasing said table in the direction of said wheel when said manual feed is released.

10. In a circular form tool grinding device of the class described, a work-guiding table, a work-grinding abrasive wheel, a profiled stop carried by said table having the form of the envelope of the work as it is to be ground, a follower finger presented to a longitudinal line on the profiled surface of said stop, means for adjusting the an-

gularity of presentation of the said wheel and the said follower to the work and to the stop respectively, means for adjustably moving said wheel toward the work along the plane of its presentation to the work, releasable manual means for feeding said work-table toward said wheel, and means biasing said table in the direction of said wheel when said manual feed is released.

11. In a circular form tool grinding device of the class described, a work-guiding table, a work-grinding abrasive wheel, a profiled stop carried by said table having the form of the envelope of the work as it is to be ground, a follower finger presented to a longitudinal line on the profiled surface of said stop, means coupling said wheel to said follower for coordinated angular adjustment relative to the work and to said profiled stop, respectively, means for adjustably moving said wheel toward the work along the plane of its presentation to the work, releasable manual means for feeding said work-table toward said wheel, and means biasing said table in the direction of said wheel when said manual feed is released.

12. In a circular form tool grinding device of the class described, a work-guiding table, a turn-table, a work-grinding abrasive wheel mounted on said turn-table for angular adjustment to the work, a profiled stop carried by said table having the form of the envelope of the work as it is to be ground, a follower finger presented to a longitudinal line on the profiled surface of said stop, a finger swivel bracket coupled to said turn-table whereby angular adjustment of both said wheel and said follower finger may be coordinated, adjustable means for synchronizing the radial swinging arc of the working contact point of said wheel with the radial swinging arc of the contact point of said finger, means for adjustably moving said wheel toward the work along the plane of its presentation to the work, releasable manual means for feeding said work-table toward said wheel, and means biasing said table in the direction of said wheel when said manual feed is released.

WALTER F. ROSS.
